UNITED STATES PATENT OFFICE

RUBIN COHEN, OF EL PASO, TEXAS, ASSIGNOR TO HAYMON KRUPP & COMPANY, OF
EL PASO, TEXAS, A CORPORATION OF TEXAS

GARMENT

Application filed January 27, 1931. Serial No. 511,587.

This invention relates to new and useful improvements in garments generally, although more particularly to a one-piece play suit or coverall.

Among the several objects of the invention are to provide a one-piece garment having a washable elastic back-band for facilitating the opening and closing of the back of the garment and providing for free and easy access; to provide such a garment which eliminates all buttons or snaps on the back except for a single button and which eliminates the well known drop seat heretofore employed having five or more buttons; and to provide such a garment having a back portion extending within and below the elastic back band and connected at its lower corners to the outside seams which unite the front and back portions of the garment, thereby holding the lower part of the back portion in snug position and yet permit of the same being properly expanded.

With these and other objects in view which will more fully appear, the nature of the invention will be more clearly understood by following the description, the appended claim, and the several views illustrated in the accompanying drawings.

In the drawings:—

Figure 1 is a front elevation of a garment constructed in accordance with my invention, Figure 2 is a rear elevation thereof,

Figure 3 is an enlarged rear elevation, parts being broken away to better disclose my invention,

Figure 4 is an enlarged sectional view taken on the line 4—4 of Figure 2, and

Figure 5 is a sectional view taken on the line 5—5 of Figure 1.

Referring to the accompanying drawings, my invention is directed to a coverall garment or the like, which includes a body portion A and a bifurcated portion B.

The body portion A comprises a front which includes front portions 5, 5, back por-

tions 6, 6 which are connected by a center seam 7, and arms 8, 8, the front and back being connected by outside seams 9, 9.

The bifurcated portion B comprises a front which includes front portions 10, 10, and back portions 11, 11 which are connected by a center seam 12, the front and back being connected by inside leg seams 13, 13, and by outside leg seams 9^a, 9^a which are continuations of the outside seams 9, 9.

The fronts of the body portion A and the bifurcated portion B are connected by an inelastic band 14, and the front portions 5, 5 and 10, 10 from the crotch 15 to the neck opening 16, are not permanently connected but the inner edge portions thereof extend across the band 14 and are detachably connected by buttons 17 or other suitable fastening means.

An elastic back band 18 extends along the upper edge portion of the back of the bifurcated portion and is secured thereto by a line of stitches 19, the ends of the band being secured against movement relative to the front of the garment by being stitched in the outside seams 9, 9.

A single snap fastener C, or other separable means, constitutes the sole means for connecting the band 18 to the back of the body portion, one part 20 of the fastener being attached to the band and the cooperating part 21 being secured to the back of the body portion on the center seam 7 thereof. Thus by means of the elastic back band and the single separable fastener, the lower portion of the back of the body portion is held in snug position and permits of said portion being properly expanded.

The lower part 22 of the back of the upper portion A extends downwardly below the elastic band 18 so as to underlap the upper part of the back of the bifurcated portion B, and the lower ends of said part 22 are free of the outside leg seams 9^a, 9^a. The lower corners of said part 22 are connected to the

front of the bifurcated portion by elastic webbings 23, 23 which function to normally retain said lower part 22 in proper wearing position and yet permit of said part becoming bowed rearwardly when desired.

It is of course to be understood that the details of structure and arrangements of parts may be variously changed and modified without departing from the spirit and scope of my invention.

10 I claim:—

In a one-piece garment, the combination with a body portion and a bifurcated portion connected together at the front, the back of the body portion underlapping the back of the bifurcated portion, elastic connections between the lower underlapping corners of the back of the body portion and the front of the bifurcated portion, an elastic back band extending along and secured to the upper edge portion of the back of the bifurcated portion and having its ends secured against movements relative to the front of the garment, and cooperating separable fastening means between the elastic band and the back of the body portion.

15 In testimony whereof, I have hereunto subscribed my name.

RUBIN COHEN.
